UNITED STATES PATENT OFFICE.

CHARLIE C. STUBBLEFIELD AND FRANK C. HAWKINS, OF ROGERS, ARKANSAS.

LOCK-NUT.

1,226,143.

Specification of Letters Patent.

Patented May 15, 1917.

Application filed September 9, 1916. Serial No. 119,297.

To all whom it may concern:

Be it known that we, CHARLIE C. STUBBLEFIELD and FRANK C. HAWKINS, citizens of the United States, residing at Rogers, 5 in the county of Benton and State of Arkansas, have invented certain useful Improvements in Lock-Nuts, of which the following is a specification, reference being had therein to the accompanying drawing.

10 The invention relates to nut locks, and has for its primary object to provide a lock of this character wherein the nut can be conveniently turned on the threaded bolt in a direction for tightening the bolt in a part 15 or piece of work, the said nut being held against working off of the bolt, and should it be desired to remove the nut from the latter, the lock can be readily detached for this purpose.

20 Another object of the invention is the provision of a nut lock of this character wherein the lock is mounted within the nut in a novel manner, and by reason of its construction, the use of locking dogs, set 25 screws, or the like are eliminated, and the lock when in the nut can not possibly work out of the same.

A further object of the invention is the provision of a nut lock of this character 30 wherein the lock is held within a suitable groove formed in one face of the nut, so that the lock is flushed with the grooved face of the nut, and will serve to automatically fasten the nut in its adjusted position, 35 when turned upon the bolt.

A still further object of the invention is the provision of a nut lock of this character which is simple in construction, thoroughly reliable and efficient in its purpose, strong, 40 durable, and inexpensive in manufacture.

With these and other objects in view, the invention consists in the features of construction, combination, and arrangement of parts, as will be hereinafter fully described, illustrated in the accompanying drawings, and pointed out in the claim hereunto appended.

In the accompanying drawing:

Figure 1 is an elevation of a nut lock constructed in accordance with the invention, 50 upon a bolt.

Fig. 2 is a side elevation of the bolt and nut.

Fig. 3 is a sectional view on the line 3—3 55 of Fig. 1.

Fig. 4 is a fragmentary sectional view on the line 4—4 of Fig. 2.

Similar reference characters indicate corresponding parts throughout the several views in the drawing.

Referring to the drawing in detail, A 60 designates a bolt which is provided along its threaded portion with longitudinal grooves 5, and upon this threaded portion is adjustably mounted a nut 6, carrying a lock hereinafter described.

The nut 6 in its outer face, is formed with an annular groove 7, which is disposed concentrically of the bolt receiving opening, and intersecting this groove 7, and the bolt receiving opening in said nut is an angular cut away portion 8, while at a point approximately diametrically opposed said cut away portion, in the bed, or bottom of the groove 7, is a socket 9, for a purpose presently described.

70 Mounted for relative movement within the groove 7 is a lock which comprises a substantially semi-circular resilient member 10, which is preferably formed from a wire 75 having the requisite resiliency, bent at one end thereof, to form a right angular anchoring terminal 11, which is provided with a bifurcation, to provide slightly spread resilient fingers 12, and this terminal 11 with 80 its fingers 12, is forced into the socket 9, so that the member 10 is fastened in place 85 to lie within the groove 7, while the other end of the member 10 is bent inwardly to form a locking terminal 13, having a 90

beveled face 14, and this terminal lies within the cut away portion 8, in the nut 6, so that its beveled portion will protrude into the bolt receiving opening in the said nut to co-act with any one of the longitudinal 95 grooves 5, in the threaded portion of the bolt A, for the positive locking of the nut upon the bolt on the turning of said nut in a direction for the tightening of the bolt in a piece of work or part.

100 The groove 7 in the outer face of the nut 6 is of a depth so that the locking member 10, when therein, will be substantially flush with the outer face of said nut.

105 It will be apparent that this locking member can be readily removed from the groove by the use of a suitable implement, or tool, adaptable for prying the member 10 without the socket 9, and the groove 7 in the outer face of the nut.

From the foregoing it is thought that the construction and manner of operation of the nut will be clearly understood, and therefore, a more extended explanation has been 5 omitted.

What is claimed is:—

The combination with a bolt, having a threaded portion provided with longitudinally disposed grooves, of a nut adjustably 10 mounted on the threaded portion of the bolt, and having an annular groove in its outer face concentrically of the bolt, and also provided with a socket and a cut away portion diametrically opposite each other, the cut

away portion inter-secting the opening in 15 the nut for the bolt, and said groove, a resilient semi-circular locking member seated within the groove, a right angular bifurcated terminal on said member, engaged in the socket, and an inwardly bent locking 20 terminal on said member, and lying within the cut away portion to co-act with the grooves in the bolt.

In testimony whereof we affix our signatures.

CHARLIE C. STUBBLEFIELD.
FRANK C. HAWKINS.
